PERCY M. ELLIOTT, DECEASED, ASSIGNOR TO CAMEL COMPANY, OF CHICAGO,
ILLINOIS, A CORPORATION OF ILLINOIS.

SAFETY TOP GUIDE FOR CAR DOORS.

Application filed May 3, 1919. Serial No. 294,495.

To all whom it may concern:

Be it known that I, Percy M. Elliott, a citizen of the United States, residing at Chicago, in the county of Cook and State of Illinois, have invented certain new and useful Improvements in Safety Top Guides for Car Doors, of which the following is a specification.

The object of the present invention is to provide a combined water-proofing and emergency supporting top guide for car doors which will remain normally free-running in the sense that its bar carried by the door and its guide rail mounted on the car are free from vertical support, the one upon the other, so long as the normal roller or other traversing support remains in service, but nevertheless has its said bar and rail so interlocked vertically as to prevent the door dropping from the car in case the traversing support is carried away or seriously impaired by accident, and so interlocked horizontally that it will on the one hand afford a more effective barrier to weather elements, and on the other hand will resist lateral displacement of the door from its guide rail when the latter assumes emergency support of the door.

Another object of the invention is to realize the conditions above stated without material change in the vertical dimensions of the door or doorway, as by having the interlocking portions of the door and its guide located below the top of the door. In some instances, the horizontal interlock between the parts will be such as to normally resist inward chafing of the door against the car, as well as outward tipping of the door, while still maintaining the guide free from the vertical load of the door.

In carrying out the invention, the guide rail carried by the car is made with a vertically opening trough that receives the rib, lip, or flange extending from the curb rail on the door with a sufficient vertical offset therefrom to adapt it to enter said trough and to be confined horizontally by the sides of the latter, these members being upon a car and door having other and independent means affording normal vertical support to the door, so that the trough and the cooperating lip or flange are normally out of vertical bearing and come into vertical support one upon the other only under emergency

impairment of the normal support of the door; the confinement of the door by the guide rail being such that the door cannot escape laterally therefrom, either inwardly or outwardly, at the time of such emergency support, and the upper portion of the door being recessed to admit the interlocking parts within its outer plane.

Several embodiments of the invention are shown in the accompanying drawings by way of illustration. In said drawings—

Figure 1 shows a vertical section of a door and its associated parts in a freight car structure to which the present invention is applied; and

Figures 2 to 4 are similar views of the upper portion of the door and appurtenant parts of the car structure with modified constructions of top guide applied thereto.

According to Figure 1, a car structure A has a sliding door B associated therewith through any approved means such as traversing roller support C, which is shown at the bottom but which may be at the top of the door. In order to confine the top of the door against outward tipping, it is customary to provide a curb-bar on the door and a guide rail on the car overlapping the same.

According to the present invention the guide rail 1 is provided for this purpose, but to enable it to serve the additional purposes incident to the present invention, it is provided with a trough 1^a which opens vertically, its opening being presented upwardly in the several embodiments here selected for illustration, while the curb-bar 2 on the door is deflected to provide a depending flange or tongue 2^a (Figs. 2, 3, and 4), or is formed with a bulb 2^a (Fig. 1) presented to the opening of the trough and in such relation to the latter that in addition to the horizontal engagement of the curb-bar by the guide rail which prevents the door from tipping outward as is usual, and in addition to vertical interlock, so that the curb-bar can rest upon the guide rail in case the door is dropped by its normal support, the curb-bar on the door is adapted to drop into the trough in case of an emergency, and when the parts are so engaged even though the door be entirely free at bottom and swing outwardly, it cannot be displaced from its emergency support thus provided.

In addition to serving as an interlocking

emergency support, the parts, when formed as above described, provide a more efficient weather-proofing for the top of the door, particularly because of the vertical overlapping of the parts. As shown in some of the embodiments, for instance Figure 3, the portion 2^a of the curb-bar may dip sufficiently into the trough 1^a of the guide rail to provide chafing surfaces which act in the normal condition of the door and so serve as means for preventing the door from chafing the side of the car.

Various forms of structural metal may be employed in realizing the several features of the present invention, and various ways of applying the same to the car structure and its door may be resorted to.

According to Figures 1, 2, and 3, the guide rail secured to the side plate of the car and the curb-bar attached to the inner face of the door and extending across the top thereof are offset outwardly sufficiently to permit the inter-engaging parts to be dropped below the top of the door into a recess provided to receive them. According to Figure 4 a similar result is obtained by securing the curb-bar to the outer face of the door.

In wooden doors the upper portion of the outer sheathing of the door is cut away to provide the recess to receive the inter-engaging parts. The advantage of this recess is that it permits the interlocking parts to be brought substantially within the overall dimension of the car, measured transversely through its door.

According to Figure 3, the curb-bar is se-

cured to the inner face of the door, but a special form of guide rail, depending directly from the side plate of the car and offset inwardly into a recess formed in the upper end of the door, adapts the device to be used in an arrangement of door which is wholly within the outside lines of the car structure.

The various forms herein illustrated will be sufficient to indicate the wide variety of arrangements that may be devised for realizing the conditions of the present invention.

I claim:

In combination with a car door having a normal traversing support, a combined weather proofing and emergency supporting top guide comprising a curb-bar and a guide-rail, said curb-bar carried by the car door and having a vertically presented portion spaced from the door, said guide rail carried by the car in position to overhang the top of the door; said curb-bar and guide-rail being normally free from vertical support, one upon the other, but adapted the one to rest upon the other in an emergency, and the guide-rail being constructed to project beneath and overlap vertically both inner and outer faces of the vertically presented portion of the curb-bar, the upper portion of the door being recessed to admit said interlocking parts within the plane of its outer face.

Signed at Chicago, Illinois, this 22nd day of April, 1919.

PERCY M. ELLIOTT.
